UNITED STATES PATENT OFFICE

FLORENCE N. LEWIS, OF NEW YORK, N. Y.

DESIGN FOR A COMBINATION PERFUME BOTTLE AND CONTAINER THEREFOR

Application filed November 5, 1931, Serial No. 41,629, and in France August 20, 1931. Term of patent 7 years.

To all whom it may concern:

Be it known that I, FLORENCE N. LEWIS, a citizen of the United States, residing at New York, New York, have invented a new, original, and ornamental Design for a Combination Perfume Bottle and Container Therefor, of which the following is a specification, reference being had to the accompanying drawing, forming part thereof.

Fig. 1 is a side elevation of the container portion of the design with the cover of the container closed.

Fig. 2 is a top plan view of the same.

Fig. 3 is a perspective view of the combination perfume bottle and container therefor, with the cover of the container in open position.

I claim:

The ornamental design for a combination perfume bottle and container therefor, as shown.

FLORENCE N. LEWIS.
